D. E. LEVERETT

STOVE DOOR ATTACHMENT

Filed Aug. 7, 1923

Fig. 1.

Dolly E. Leverett,

INVENTOR

WITNESS

Hyman Berman
A. L. Inc.

Clarence A. O'Brien,

ATTORNEY

UNITED STATES PATENT OFFICE.

DOLLY ELSIE LEVERETT, OF KALAMAZOO, MICHIGAN.

STOVE-DOOR ATTACHMENT.

Application filed August 7, 1923. Serial No. 656,184.

To all whom it may concern:

Be it known that I, DOLLY ELSIE LEVERETT, a citizen of the United States, residing at Kalamazoo, in the county of Kalamazoo, 5 and State of Michigan, have invented certain new and useful Improvements in Stove-Door Attachments, of which the following is a specification.

This invention relates to stove door attachments and has particular reference to the provision of means for preventing the falling of ashes and live coals out of a stove door opening when the door is opened.

It is well known that ashes and live coals often fall on to the floor through a stove door opening when the door is opened, thus causing considerable annoyance and often being the cause of serious fires. It is accordingly an object of the present invention 20 to provide a simple and efficient means for shaking the ashes and coals into the fire pot as the stove door is opened so as to prevent falling of the ashes and coals on to the floor, and to thereby eliminate the occurrence of 25 fire from this source.

Another object of the invention is to provide a vertically swinging shield upon the interior of a door, and means operated by the latch of the door for swinging said shield so as to shake the ashes and coals back into the fire pot.

Other objects will appear as the nature of the invention is better understood, and the same consists in the novel form, combination and arrangement of parts herein-after more fully described, shown in the accompanying drawings and claimed.

In the drawings, wherein like reference characters indicate corresponding parts throughout the several views,

Figure 1 is a view of the interior of the stove door, the door being indicated by dotted lines.

Figure 2 is a side elevational view, partly broken away, of the device shown in figure 1.

Figure 3 is an enlarged perspective view of the latch for holding the guard plate in its inoperative position when the stove door is closed.

Figure 4 is an enlarged perspective view of the clip for holding the toggle lever in engagement with the latch; and

Figure 5 is a perspective view of the

clip for holding the toggle member connected with the door latch.

Referring more in detail to the drawings, the invention consists of a guard plate 5 preferably constructed of sheet metal so as to fit within the door 6 of a stove. The 60 plate 5 is preferably cut away at its upper edge, centrally of the latter, as at 7 so as to not obstruct the flow of air into the stove through the usual damper 8, and the lower edge of this plate is formed with an inclined ledge or flange 9 upon which the ashes may settle. As shown in Figures 1 and 2, the vertical edges of the plate 5 are also provided with inturned flanges as at 10, and the ends of a spring 11 extend 70 through the lower portions of the flanges 10 and are provided with rounded heads 12 upon their free ends adapted to impinge against the inner surfaces of the sides of the door 6 for supporting the guard plate 75 5 for pivotal movement in a vertical direction. The spring member 11 is preferably constructed of suitable resilient wire normally expanded to a greater length than the width of the door so that the attachment is 80 snapped into place, and the central raised portion of this spring carries a suitable resilient catch 12' adapted to engage over the edge of the door at the damper opening 85 when the guard plate 5 is swung to a vertical inoperative position, thereby preventing displacement of the guard plate out of its proper position.

Attached to one side of the guard plate 5 is a link 13 forming part of a toggle lever, 90 the other link 14 of which is pivoted to the upper end of the link 13 as at 15. The lower end of the link 14 is adapted to impinge against a sliding collar 16 arranged upon link 13 when the toggle lever is straightened 95 as shown in Figure 5, and a spring 17 is disposed about the link 13 between a shoulder 18 and the sliding collar 16 so that the latter is pressed against the lower end of the link 14 for resiliently holding the toggle lever 100 against being broken. The upper end of the link 14 is bifurcated so as to embrace the inner end portion of the usual latch 19 of the stove door, and is held in this position by means of a clip 20 which is held on the outer end of the latch 19 by means of a screw 21 which passes through a threaded opening 22 in the bifurcated end of the link 105

14 and into a threaded opening 23 in said clip 20.

As shown in Figure 1, the guard plate 5 is vertical when the links of the toggle lever 5 are broken and the latch 19 is in latching position. When so disposed, the catch 12' is engaged with the door and the door is closed. With the parts so disposed, it will be seen that the ashes and coals may fall 10 upon the ledge 9 so that when the door is opened these ashes will be effectively shaken back into the fire pot by tilting of the guard plate 5 inwardly. This tilting movement is effected by releasing the catch 12' and then 15 turning the knob 24 of the door latch 19, whereupon the toggle lever is straightened as shown in Figure 5, for swinging the guard plate 5 inwardly as indicated by dotted lines in Figure 2 the clip 12 holding the 20 lever 14 in engagement with the latch at all times. In this way the ashes are effectively shaken back into the fire pot, and should any coals attempt to fall out through the 25 door opening, they will also be forced or shaken backwardly into the fire pot by the plate pressing against the coals. The guard plates will be held in its inwardly swung position by means of the spring 17 and collar 16 which holds the toggle lever in 30 straightened condition as shown in Figure 5, and the door of the stove may then be readily opened without danger of ashes falling upon the floor or fire being caused by the falling of hot coals thereon. The guard plate 35 swings with the door following the above movement and retains this inclined position relative to the door, until the same is closed and the latch operated. A reversal of this 40 operation will cause the toggle lever to be broken for swinging the guard plate 5 back to vertical position and for operating the latch 19 for holding the door 6 closed. Following the closure of the door and operation of the latch to lock the same, the catch 12' 45 will be reengaged with the door by forcing the bevelled end 12'' over the edge of the cut away portion 7.

From the foregoing description, it will be seen that I have provided a fire preventative which is operated automatically upon 50 opening a stove door in the usual manner and by means of which the ashes and live coals are prevented from escaping into the room, thereby protecting the woodwork, furniture and rugs from considerable damage.

Minor changes may be made without departing from the spirit and scope of the invention as claimed.

What I claim as new is:—

60 1. A stove door attachment of the class described comprising a guard plate adapted to be positioned on the lower part of a stove door behind the latter, means carried by said guard plate and engageable with the inner surfaces of the sides of the stove door for

mounting said guard plate for a vertical swinging movement and means operatively connected to the guard plate and adapted for connection with the usual door latch for causing swinging movement of the guard plate inwardly upon releasing of said latch. 70

2. A stove door attachment of the class described comprising a guard plate adapted to be positioned on the lower part of a stove door behind the latter, means carried by 75 said guard plate and engageable with the inner surfaces of the sides of the stove door for mounting said guard plate for a vertical swinging movement and means operatively connected to the guard plate and adapted for connection of the usual door latch for causing swinging movement of the guard plate inwardly upon releasing of said latch, the means for mounting the guard plate for swinging movement comprising a spring 80 member attached to and having its ends projecting beyond the side of the guard plate. 85

3. A stove door attachment of the class described comprising a guard plate adapted to be positioned on the lower part of a stove door behind the latter, means carried by said guard plate and engageable with the inner surfaces of the sides of the stove door for mounting said guard plate for a vertical swinging movement, and means operatively connected to the guard plate and adapted for connection with the usual door latch for causing swinging movement of the guard plate inwardly upon releasing of said latch, the means for mounting the guard plate for swinging movement comprising a spring 90 member attached to and having its ends projecting beyond the sides of the guard plate, and a catch carried by the central portion of said spring member for engaging 95 over the door at the damper opening of the latter for releasably holding the guard plate in an inoperative vertical position. 100

4. A stove door attachment of the class described comprising a guard plate adapted to be positioned on the lower part of a stove door behind the latter, means carried by 110 said guard plate and engageable with the inner surfaces of the sides of the stove door for vertical swinging movement, and means operatively connected to the guard plate and adapted for connection with the usual door latch for causing swinging movement of the guard plate inwardly upon releasing of said latch, the means for swinging the guard plate comprising a toggle lever having 115 means at one end thereof for facilitating its detachable connection to the door latch. 120

5. A stove door attachment of the class described comprising a guard plate adapted to be positioned on the lower part of the stove door behind the latter, means carried by said guard plate and engageable with the inner surfaces of the sides of the stove 130

door for mounting said guard plate for vertical swinging movement and means operatively connected to the guard plate and adapted for connection with the usual door latch for causing swinging movement of the guard plate inwardly upon releasing the latch, the means for swinging the guard plate comprising a toggle lever having means at one end thereof for facilitating its detachable connection to the door latch, and means associated with said toggle lever for automatically retaining the same in straightened position when the guard plate is swung inwardly.

In testimony whereof I affix my signature.

MRS. DOLLY ELSIE LEVERETT.
